UNITED STATES PATENT OFFICE.

CARL P. ANDERSON, OF EVERETT, MASSACHUSETTS.

MILLSTONE.

SPECIFICATION forming part of Letters Patent No. 773,363, dated October 25, 1904.

Application filed January 22, 1904. Serial No. 190,150. (No model.)

To all whom it may concern:

Be it known that I, CARL P. ANDERSON, a citizen of the United States, and a resident of Everett, in the county of Middlesex and State 5 of Massachusetts, have invented certain new and useful Improvements in Millstones, of which the following is a specification.

This invention relates to improvements in millstones for grinding paint, grain, or other 10 materials, and it relates especially to the construction of the feed-furrows in such a manner as to render them capable of being readily dressed from time to time as the face of the stone wears out, as will hereinafter be more 15 fully shown and described, reference being had to the accompanying drawings, wherein—

Figure 1 is a top plan view of one of a pair of my improved millstones. Fig. 2 is a cross-section on the line 2 2 in Fig. 1, showing the 20 feed-furrows filled with a suitable material softer than the body of the stone; and Fig. 25 3 is a cross-section on the line 3 3 in Fig. 1.

Similar letters refer to similar parts wherever they occur on the different parts of the 25 drawings.

The invention relates especially to molded millstones made of emery composition or the like, but may also be applicable to natural material stones without departing from the 30 essence of my invention.

In the drawings, A represents a preferably molded millstone on which B is the central perforation, as usual. On the face of such stone is arranged a series of tangential feed-furrows C C, extending from the middle of 35 the stone to nearly the outer periphery thereof with a solid portion A' being left in the stone at the outer end of each feed-furrow, as shown in Figs. 1 and 2. The said feed-furrows 40 extend only partially through the thickness of the stone, leaving a solid portion A'' at the bottom of each feed-furrow, as shown in the drawings. The said feed-furrows are afterward filled with suitable material or com- 45 position D softer than the body of the stone, and for such purpose I may use cement, sulfur, or any desired material or composition that is softer and more readily shaped or dressed than the body of the stone. The face of such 50 composition in the feed-furrows can readily be dressed to the inclination, as shown at d in Fig. 3, and this can readily be done by any

suitable tool, such as a carpenter's chisel, a scraper, or the like.

In ordinary millstones, either natural or hand composition ones, the feed-furrows are 55 cut directly in the face of the stones by a pick or similar tool, and this has to be repeated from time to time during the wear and subsequent refacing of the stone, which renders 60 the operation both costly and time-consuming. By making tangential furrows in the stone and filling the same with a material, substance, or composition considerably softer than the body of the stone, such feed-furrows can be 65 readily shaped or dressed from time to time as occasions may require simply by scraping off or removing a portion of the softer material D contained in said feed-furrows, as 70 above described. In addition to such tangential feed-furrows the face of the stone is provided with the ordinary smaller furrows, as is common in millstones.

Between the main furrows C and extending from the perforation B to the periphery of 75 the molded millstone and also extending from the outer ends of the said main furrows to said periphery are auxiliary furrows, as E, represented as tangential. These auxiliary furrows, like the main furrows, are situated in 80 the upper or working face of the stone and serve their usual purpose in grinding.

What I wish to secure by Letters Patent and claim is—

In a millstone, a circular body of suitable 85 material, having a central opening, a series of main feed-furrows extending outward from said opening toward but short of the periphery of said body, and a series of auxiliary furrows extending outward from said opening to 90 the periphery between the furrows and also extending outward from the outer ends of the main feed-furrows to said periphery, whereby a portion of the stock of the body will be left between the outer end walls of the several 95 feed-furrows and the periphery of said body, and filling material in the furrows, softer and more readily shaped or dressed than said body.

In testimony whereof I have affixed my signature in presence of two witnesses.

CARL P. ANDERSON.
